UNITED STATES PATENT OFFICE

154,954

DESIGN FOR A BRACELET OR SIMILAR ARTICLE

Harry Reinstein, Rye, N. Y.

Application April 7, 1949, Serial No. 1,851

Term of patent 3½ years

(Cl. D45—4)

To all whom it may concern:

Be it known that I, Harry Reinstein, a citizen of the United States of America, residing in Rye, county of Westchester, and State of New York, have invented a new, original, and ornamental Design for a Bracelet or Similar Article, of which the following is a specification, reference being had to the accompanying drawing, forming part thereof, wherein

I claim:

The ornamental design for a bracelet or similar article, substantially as shown.

HARRY REINSTEIN.
